UNITED STATES PATENT OFFICE.

GEORGE P. ERHARD, OF BROOKLINE, MASSACHUSETTS, ASSIGNOR TO THE STAFFORD COMPANY, OF READVILLE, BOSTON, MASSACHUSETTS, A CORPORATION OF NEW JERSEY.

WARP STOP-MOTION FOR LOOMS.

1,174,928.

Specification of Letters Patent.

Patented Mar. 7, 1916.

Application filed July 17, 1914. Serial No. 851,630.

To all whom it may concern:

Be it known that I, GEORGE P. ERHARD, a citizen of the United States, residing at Brookline, in the county of Norfolk, State of Massachusetts, have invented a certain new and useful Improvement in Warp Stop-Motions for Looms, of which the following is a specification, reference being had therein to the accompanying drawings.

In the majority of the warp stop motions that in practice are employed in looms the drop-wires are disposed in parallel lines or banks, applied to the warp-threads in the interval between the lease-rods, and usually hung upon the lower planes of the lease at front and rear, respectively, of the intersection of the lease. In some cases the drop-wires are made with short upper ends designed to terminate below the upper planes of the lease adjacent the crossing, the aim being to reduce the extent to which the warp-threads are exposed to chafing. As applied to the warp-threads close to the intersection of the lease, the pendant lines of drop-wires hang close together, and the combined presence of the drop-wires and the crossed warp-threads fills the short interval between the lease-rods with a closely-packed assemblage of warp-threads and drop-wires, while below the warp-threads there is a congested mass of drop-wires, and also the drop-wire guide-bars. The close massing of the threads and drop-wires has several drawbacks, one thereof being that it interferes with access to the drop-wires, and with the operations of repairing broken warp-threads and rethreading them through their drop-wires. Another is the tendency to collection of lint. A further drawback is the fact that even when as aforesaid, the drop-wires are hung upon the lower planes of the warp-threads at the opposite sides of the intersection of the lease, and even when they are formed with short upper ends to avoid contact of their upper ends with the threads in the upper planes, nevertheless in the working of a loom the movements of the warp-threads cause the drop-wires to jump vertically so that their upper ends rise between the threads in the upper planes. Many of the drop-wires remain up in this position. As a result of such jumping, and as a result of the drop-wires remaining elevated, there occurs more or less chafing of the warp-threads.

The general object of the invention is to provide in a warp-stop motion a warp-dividing rod or rods of novel and improved character and construction adapted to render it practicable to locate all or some of the drop-wires in line vertically with the lease-rods, or one of the latter, so as to leave the space between the lease-rods either wholly unencumbered with drop-wires, or less crowded therewith, thereby obviating the close massing or congestion of warp-threads and drop-wires above mentioned. I attain this object by constructing the lease-rods, or it might be either of them, of L-shape in cross-section and arranging and combining the same as disclosed hereinafter.

One embodiment of the invention is shown in the drawing, which represents the same applied in connection with parts of a well-known form of warp stop motion at present in use and substantially shown and described in U. S. Letters Patent No. 1,032,542, dated July 16, 1912. The view is a section in the direction from front to rear, and includes only such parts and features as are useful to be shown in order to make a clear disclosure of the nature and relations of the invention.

The drawing shows the drop-wires 1, 1, disposed in the customary number, two, of banks and hung upon the lower planes of the leased warp-threads 2, 2, at front and rear respectively of the intersection of the lease, with one bank in line vertically with a portion of one lease-rod 3 and the other bank in line vertically with a portion of the other lease-rod. The guide-bars 4, 4, extending through the slots of the drop-wires are vertically below the said portions of the lease-rods. The clearance for the upper ends or heads of the drop-wires is provided by constructing the lease-rods of angle-iron, L-shaped in cross-section, and disposing them as shown, or substantially as shown, with one flange thereof upright and the other horizontal. The drop-wires are engaged with the warp-threads with their heads in line with the horizontal flanges, and adapted to work within the internal angle between the two flanges of each lease-rod. With the horizontal flanges facing each other as shown, access to the warp-threads and drop-wires through the opening between the lease-rods is facilitated. The height of the horizontal flanges of the lease-rods above the

lower edges of the vertical flanges permits a sufficient extent of jumping of the drop-wires in response to jerking movements of the warp-threads during the weaving action 5 to avoid cutting or chafing the warp-threads against the inner edges of the eyes of the drop-wires. The condition of the drop-wires may be observed by parting more or less the upper planes of warp-threads between the two lease-rods and looking down 10 between the latter. As will be observed, the parting of the warp-threads of the upper planes will expose to view more or less completely from above the upper portions of the drop-wires notwithstanding the fact that they are in line with the horizontal flanges 15 3, 3, of the lease-rods.

It will be obvious from the drawing that the interval between the lease-rods is open 20 and clear, with much improved conditions for the warp-threads and the action of the drop-wires, and with ample opportunity for lint to fall down entirely clear of the warp-threads and drop-wires. Upon occasion, additional banks of drop-wires may be employed adjacent the intersection of the lease, thus facilitating the production of high-slayed goods.

As shown, the upward movement of the 30 drop-wires is limited by contact of the bottoms of the slots in the drop-wires with the under edges of the guide-bars 4, 4. Other provision may be made for limiting the said movement, if desired.

Referring briefly to the features in general as shown in the drawings,—the warp-threads 1, 1, are shown divided into two planes, as common, by a warp-separating rod *a* located adjacent the lease-rods 3, 3. 35 The latter are shown supported at their ends by the warp stop motion stand *b*, constructed at its top with open-topped seats or sockets 3^a, 3^a, for the corresponding ends of the lease-rods. The said seats or sockets are 40 formed to retain the lease-rods in their working positions as shown. An intermediate warp-rest *c* of usual character is supported at its end by the stand, the latter having a socket *c'* for such end located between the sockets 3^a, 3^a. In common practice, the 45 top of the warp-rest *c* frequently is located a little below the intersection of the lease, as in the drawings. The guide-bars 4, 4, extending through the slots of the drop-wires 50 are supported at their ends in sockets or seats 4^a, 4^a, with which stand *b* is constructed. At *d*, *d*, are the back-stop bars for the lower ends of the drop-wires, supported at 55 their ends in sockets with which stand *b* is

constructed, with said ends secured in such 60 sockets by clamping screws *e*, *e*. At *f* is the reciprocating feeler, comprising a rod supported by its end resting upon a horizontal ledge *g* upon stand *b*, and reciprocated in usual manner horizontally along such ledge, 65 to and fro beneath the normal positions of the drop-wires suspended by the warp-threads. The drawing shows only a portion 70 of the means for communicating the reciprocating movement to the feeler, such portion comprising the connecting-rod *h*, the arm *i* to which the connecting-rod is connected pivotally, and the rockshaft *k* upon which the said arm is fixed. The means for rocking the rockshaft *k* and bringing 75 about the stoppage of the loom may be as in the patent aforesaid, or of any other approved character.

I claim as my invention:

1. A warp-stop-motion for looms having 80 in combination, a rod of L-shape in cross-section, the free edge of one flange thereof serving as a warp-guide, and drop-wires engaged with the warp-threads with their heads in line with the other flange and 85 adapted to work within the internal angle between the two flanges.

2. A warp-stop-motion for looms having 90 in combination, a warp-dividing rod of L-shape in cross-section, the free edge of one flange thereof serving as a guide for one 95 plane of the warps and the exterior of the other flange serving as a guide for the other plane of the warps, the drop-wires engaged with the warp-threads with their heads in line with the other flange and adapted to work within the internal angle between the 95 two flanges.

3. A warp-stop-motion for looms comprising in combination, a pair of lease-rods 100 respectively of L-shape in cross-section with their internal angles facing each other and with one flange of each serving as a guide for one plane of the warps and the vertical edge of the other flange of each serving as a 105 guide for the other plane of the warps, and drop-wires in connection with each of the said rods engaged with the warp-threads with their heads in line with the first mentioned flange and adapted to work within 110 the internal angle between the two flanges.

In testimony whereof I affix my signature in presence of two witnesses.

GEORGE P. ERHARD.
